NEEDLE BED CONSTRUCTION

Ladislaus Robaczynski, Brooklyn, N. Y.

Application December 10, 1935, Serial No. 53,704

7 Claims. (Cl. 66—115)

This invention relates to new and useful improvements in knitting machines, and more particularly it pertains to a novel construction of needle bed therefor.

5 A needle bed or plate for knitting machines, particularly of the, "links-links" type, consists of a relatively long and narrow body portion on which is suitably formed a plurality of spaced upstanding ribs. This construction provides a plurality of channels or grooves between the ribs, which channels or grooves form slideways for 10 needles and needle jacks.

In actual practice, it has been found necessary to employ some means to retain the needles and 15 needle jacks in position in the channels or grooves, particularly against a tendency to rise out of them when they are moved therewith. This retaining means generally consists of a retaining strip which extends lengthwise of the 20 needle bed or plate and overlies the channels or grooves. The needles and jacks lie beneath this retaining strip and are prevented thereby from displacement relatively to the channels or grooves.

In the most commonly employed construction, 25 the top face or edge of the ribs is cut away to provide a seat for the retaining strip and the side walls of this seat are undercut in such a manner that in effect, a channel which is of dovetail cross-sectional shape is formed, which channel 30 extends throughout the length of the needle bed or plate. In assembling such a construction, one end of the retaining strip, which has beveled side edges, is inserted into one end of the dovetail channel and the strip is driven home, it being in 35 its proper operative position when it is entirely received within the dovetail channel.

The retaining strip, by reason of its extreme 40 length, was of a more or less flexible nature and either its placement in operative position or its removal therefrom, was not easily accomplished and often serious damage to one or another of the parts resulted from such operations.

It is the primary object of this invention to 45 simplify the construction of this particular portion of a knitting machine bed, and more particularly, to render more easily accomplished, the placement and removal of the retaining strip to and from its operative position.

A feature of the invention resides in a novel construction whereby the retaining strip per se assumes its operative position immediately it is 50 placed upon the needle bed, it not being necessary to impart any degree of longitudinal movement thereto as is necessary in the heretofore employed construction.

A further feature of the invention resides in a novel form of fastening means for securing the retaining strip in position, which fastening means is also so constructed as to provide the necessary rigidity to prevent buckling or other distortion of 5 the retaining strip.

A still further feature of the invention resides in a novel construction whereby the several parts may be readily and easily assembled or disassembled without danger of injury thereto. 10

Other features of the invention relate to certain novel and improved constructions, arrangements and combinations of parts hereinafter described and particularly pointed out in the claims, the advantages of which will be readily understood 15 and appreciated by those skilled in the art.

The invention will be clearly understood from the accompanying drawing illustrating the invention in its preferred form and the following detailed description of the constructions therein 20 shown.

In the accompanying drawing,

Figure 1 is a fragmentary top plan view of a needle bed and retaining strip constructed in accordance with the present invention. 25

Figure 2 is a transverse sectional view on a slightly enlarged scale taken substantially on the line 2—2 of Figure 1, and;

Figure 3 is a distended fragmentary perspective view on an enlarged scale showing a section of 30 the needle bed, the retaining strip and fastening member.

The needle bed which is designated 10 consists of a relatively long narrow member. The reference character 12 designates a comb plate which, 35 although herein shown as of special construction, constitutes the subject matter of a co-pending application filed by me, December 13, 1935 Serial No. 54,185.

The needle bed or plate is formed with a plurality of spaced ribs 14 which form intervening channels 16. These channels 16 provide slideways for needle jacks and needles, the latter, in the present instance, being illustrated as of the double latch type. Machines of the type with 40 which the needle bed of the present application is particularly intended for use, employ two such needle beds and the needles are transferable from one bed to the other during the knitting operation. 45

In the present embodiment of the invention, the ribs 14 are cut out as designated at 18 in Figure 3 to provide a seat extending lengthwise of the needle bed or plate, said seat having but a single rear wall. This wall is designated 20 and, as 50 55

shown in Figures 2 and 3, is undercut or angularly disposed.

Formed on certain of the ribs 14 there are upstanding lugs 22, and the inner wall of each of these lugs 22 is undercut as at 24 to provide an inwardly disposed angular face which is adapted to cooperate with the undercut rear wall 20 of the seat for a purpose to be hereinafter described.

The reference numeral 26 designates a retaining strip. This member is formed of relatively thin metal and extends preferably throughout the entire length of the needle bar, although it may terminate short of the ends if desired, so long as it overlies all of the channels 16. The retaining strip 26 is provided with a plurality of elongated openings 28 which are spaced from each other a distance equal to the spaces between the lugs 22, heretofore mentioned. These openings 28 are elongated in a direction transversely of the retaining strip 26 and are adapted to receive the lugs 22 in a manner which will permit of lateral movement of the retaining strip relative to its seat 18.

The retaining strip 26 is adapted to overlie the slideways formed by the channels 16 between the ribs 14 at a point adjacent the front edge of the needle bed and at a point where the needle jacks, which are designated 30, connect with the needies, which are designated 32, as best illustrated in Figure 2 of the drawing to prevent displacement or disconnection of the needle jacks and needles during the knitting operation.

Means is provided to secure the retaining strip in position upon the needle bed, and this means preferably consists of a relatively flat strip of metal 34 adapted to be received on top of the retaining strip 26. This fastening member 34 has beveled side edges 35 and 36 which are adapted to cooperate with the undercut wall 20 of the seat 18 and the undercut walls 24 of the lugs 22 to lock the fastening member in position beneath the wall 20 and said lugs. The forward edge of the fastening member 34 is provided with a series of notches 40, which notches are spaced a distance equal to the distance between the lugs 22 in such manner that the fastening member 34 may be placed upon the upper face of the retaining strip 26, with the notches 40 in registration with the lugs 22, it being understood that the retaining strip is first positioned with the lugs 22 within the elongated openings 28. The fastening member, having been positioned as above described, may now be moved longitudinally of the retaining strip 26, whereupon the forward beveled edge 36 of the fastening member will pass beneath the angular walls 24 of the lugs 22 to a position in which the fastening member 34 is shown in Figure 1. This position of the fastening member will hold the retaining strip firmly to its seat 18 and lend rigidity to the assembled parts. The fastening member 34 may be provided with a rib 46 which extends throughout the major portion of the length thereof and serves to strengthen the fastening member 34.

To insure against movement of the parts, a screw or similar securing means 48 may be passed through the fastening member 34 and the retaining strip 26 into threaded engagement with a threaded opening, not shown, in the needle bed or plate 10.

From the foregoing it will be apparent that the present invention provides a new and novel construction of needle and needle jack retaining means for the needle beds of knitting machines in which the parts may be readily assembled and

disassembled without danger of damage thereto, as distinguished from the generally employed construction heretofore described.

While the present invention has been herein illustrated in its preferred form, it will be obvious that it may be practiced in other forms without departing from the scope of the appended claims.

Having thus described the invention, what is claimed as new, is:

1. A knitting machine needle bed comprising a body portion, spaced ribs on the body portion forming intervening channels for needles and needle jacks, and means for preventing displacement of needles and needle jacks relative to the channels, said means comprising a retaining strip overlying said ribs and intervening channels, said retaining strip having spaced openings therein, lugs projecting from certain of said ribs and adapted for reception in the spaced openings of the retaining strip to position the same relative to the bed, and means having engagement with said projecting lugs for securing the retaining strip in position on the needle bed.

2. A knitting machine needle bed comprising a body portion, spaced ribs on the body portion forming intervening channels for needles and needle jacks, and means for preventing displacement of needles and needle jacks relative to said channels, said means comprising a retaining strip overlying said ribs and intervening channels, said retaining strip having spaced openings therein, lugs projecting from certain of said ribs and adapted for reception in the spaced openings of the retaining strip to position the same relative to the bed, and means having engagement with said projecting lugs for securing the retaining strip in position on the needle bed.

3. A knitting machine needle bed comprising a body portion, spaced ribs on the body portion forming intervening channels for needles and needle jacks, and means for preventing displacement of needles and needle jacks relative to said channels, said means comprising a retaining strip overlying said ribs and intervening channels, said retaining strip having spaced openings therein, lugs projecting from certain of said ribs and adapted for reception in the spaced openings of the retaining strip to position the same relative to the bed, and a fastening member adapted to overlie said retaining strip and have interengagement with said lugs to secure the retaining strip to the needle bed.

4. A knitting machine needle bed comprising a body portion, spaced ribs on the body portion forming intervening channels for needles and needle jacks, said spaced ribs having a seat formed in their upper edges, the rear wall of which is undercut and means for preventing dis-

placement of needles and needle jacks relative to said channels, said means comprising a retaining strip overlying said channels, said retaining strip having spaced openings therein, lugs projecting from certain of said ribs, said lugs having an undercut wall, and said lugs being adapted for reception in the openings of the retaining strip when it is in position on the needle bed, and means slidably beneath the undercut walls of the lugs and the rear undercut wall of the seat and

upon the upper face of the retaining strip for securing the retaining strip in position, said means having beveled opposite side edges.

5. A knitting machine needle bed comprising a body portion, spaced ribs on the body portion forming intervening channels for needles and needle jacks, said spaced ribs having a seat formed in their upper edges, the rear wall of which is undercut and means for preventing displacement of needles and needle jacks relative to said channels, said means comprising a retaining strip overlying said channels, said retaining strip having spaced openings therein, lugs projecting from certain of said ribs, said lugs having an undercut wall, and said lugs being adapted for reception in the openings of the retaining strip when it is in position on the needle bed, and means slidable beneath the undercut walls of the lugs and the rear undercut wall of 10 the seat and upon the upper face of the retaining strip for securing the retaining strip in position, said means comprising a rigid bar, and a flange extending along one edge thereof, the opposite sides of said bar being beveled.

25. 6. A knitting machine needle bed comprising a body portion, spaced ribs on the body portion forming intervening channels for needles and needle jacks, said spaced ribs having a seat formed in their upper edges, the rear wall of 30 which is undercut and means for preventing displacement of needles and needle jacks relative to said channels, said means comprising a retaining strip overlying said channels, said retaining strip having spaced openings therein, lugs projecting from certain of said ribs, said lugs having an undercut wall, and said lugs being adapted for reception in the openings of the retaining strip when it is in position on the needle bed, and means slidable beneath the undercut 35 walls of the lugs and the rear undercut wall of the seat and upon the upper face of the retaining strip for securing the retaining strip in position, said means comprising a rigid bar, having 20 opposite beveled side edges, one of which is notched, said rigid bar being adapted to be placed with its notches in registration with said lugs and moved longitudinally of the needle bed with the corresponding beveled edge of the flange 30 passing beneath and having engagement with the undercut walls of said lugs.

walls of the lugs and the rear undercut wall of the seat and upon the upper face of the retaining strip for securing the retaining strip in position, said means comprising a rigid bar, a notched flange defining one edge of said rigid bar, said rigid bar being adapted to be placed with its notches in registration with said lugs and moved longitudinally of the needle bed to position the flange beneath the undercut walls of the lugs, and the seat, said rigid bar having 10 beveled side edges.

7. A knitting machine needle bed comprising a body portion, spaced ribs on the body portion forming intervening channels for needles and needle jacks, said spaced ribs having a seat 15 formed in their upper edges, the rear wall of which is undercut and means for preventing displacement of needles and needle jacks relative to said channels, said means comprising a retaining strip overlying said channels, said retaining strip having spaced openings therein, lugs projecting from certain of said ribs, said lugs having an undercut wall, and said lugs being adapted for reception in the openings of the retaining strip when it is in position on the needle 20 bed, and means slidable beneath the undercut walls of the lugs and the rear undercut wall of the seat and upon the upper face of the retaining strip for securing the retaining strip in position, said means comprising a rigid bar, having 25 opposite beveled side edges, one of which is notched, said rigid bar being adapted to be placed with its notches in registration with said lugs and moved longitudinally of the needle bed with the corresponding beveled edge of the flange 30 passing beneath and having engagement with the undercut walls of said lugs.
